UNITED STATES PATENT OFFICE.

CHARLES CORRIE BROWN, OF REVELSTOKE, BRITISH COLUMBIA, CANADA.

WINDOW-SHADE SUPPORT.

938,207.

Specification of Letters Patent.

Patented Oct. 26, 1909.

Application filed December 1, 1908. Serial No. 465,480.

To all whom it may concern:

Be it known that I, CHARLES CORRIE BROWN, a subject of the King of Great Britain, and a resident of Revelstoke, in the 5 county of Kootenay, Province of British Columbia, Dominion of Canada, have invented a new and Improved Window-Shade Support, of which the following is a full, clear, and exact description.

10 The object of the invention is to provide a new and improved window shade support, arranged for convenient up and down adjustment on the window, to allow moving the shade roller to any desired height, and to 15 permit convenient manipulation of the window shade.

The invention consists of novel features and parts and combinations of the same, which will be more fully described herein- 20 after and then pointed out in the claims.

A practical embodiment of the invention is represented in the accompanying drawings forming a part of this specification, in which similar characters of reference indicate 25 corresponding parts in all the views.

Figure 1 is a front elevation of the improvement as applied; Fig. 2 is an enlarged cross section of the same in the line 2—2 of Fig. 1; Fig. 3 is a similar view of the same 30 on the line 3—3 of Fig. 1; Fig. 4 is an enlarged side elevation of one of the brackets and its hanger for supporting the shade roller; Fig. 5 is a front elevation of the same; Fig. 6 is a sectional plan view of the 35 same on the line 6—6 of Fig. 5; Fig. 7 is an enlarged side elevation of the other bracket and its hanger; and Fig. 8 is an enlarged transverse section of the retaining clip for the pull cord.

40 The brackets A and A' are preferably of angle iron and have their ends A², A³ offset in an inward direction and secured by screws B, B', B², B³ to the sides C', C² of the window casing C, as plainly shown in Fig. 1.

45 On the brackets A and A' are mounted to slide up and down the hangers D, D', provided with bearings for the shade roller E' of a window shade E of any approved construction, preferably of the Hartshorn type, 50 and the said hangers D and D' are attached to the ends of ropes F, F' extending upwardly and passing over pulleys G, G' mounted to turn on the screws B', B², employed for fastening the upper ends A² of 55 the brackets A and A' to the sides C', C²

of the window casing C. The cord F' extends from the pulley G' to the pulley G and over the same, the said pulley G being for this purpose preferably made double, as plainly indicated in Fig. 3. The downwardly extending end of the cord F' is preferably fastened to the upwardly-extending end of the cord F, and this end of the cord F is adapted to be fastened to a retaining clip H secured to the side C' of the window casing C. The pulleys G and G' are preferably arranged in housings I, I' held on the upper ends A² of the brackets A and A', and fastened thereto by the screws B, B², as indicated in Figs. 2 and 3. Each of the 60 hangers D and D' is preferably made of a single piece of sheet metal bent into L-shape, to form an L-shaped plate D² fitting the back and the side flange of the corresponding bracket A or A', as plainly indicated in 65 Figs. 4, 5, 6 and 7, it being understood that by having the offset ends A², A³, the brackets A and A' are spaced from the faces of the sides C' and C², to accommodate the plate D². The plate D² is provided with flanges 70 D³, D⁴, bent over the side edges of the corresponding bracket A, A', so as to hold the hanger in position on the corresponding bracket A or A' and at the same time allow 75 convenient up and down sliding of the hanger on its bracket. The plate D² terminates in a bearing D⁵ for the corresponding end of the shade roller E', it being understood that the bearing D⁵ of the hanger D receives the non-turning spindle of the 80 shade roller E' (see Figs. 1 and 7), while the bearing D⁵ of the other hanger D' is arranged for receiving the turning spindle of the shade roller A' (see Figs. 1 and 4). Now by the arrangement described very 85 strong, durable and yet light brackets A and A' are provided on which the hangers D, D' can slide easily up and down without wabbling, it being understood that by the operator pulling or releasing the end of the 90 cord F the hangers D and D' are caused to slide up and down on the brackets A or A', to bring the shade E into the desired position on the window. It will further be noticed that by the arrangement described, the 95 shade E can be manipulated in the usual manner without the slightest interference by the window shade support.

It is understood that after the hangers D, D' have been adjusted to the desired height, 100

the end of the cord F is secured to the retaining clip H, to hold the hangers in the adjusted position.

The screws B, B', B² and B³ pass through 5 elongated openings in the brackets A, A' to allow adjustment of the said brackets toward or from each other to suit shade rollers of different lengths.

Having thus described my invention, I 10 claim as new and desire to secure by Letters Patent:

1. A window shade support, comprising a pair of brackets of angle iron and each having its ends set off and secured to the 15 sides of the window casing, hangers mounted to slide on the brackets and having bearings for the shade roller, each hanger having an L-shaped plate fitting adjacent the back and angular side of the corresponding bracket, the plate being provided with bent over flanges fitting the side edges of the brackets, cords secured to the said brackets, and a pulley on the upper end of each of the brackets and over which passes the adjacent cord, one of said cords extending 20 across the top of the window casing and over the other pulley.

2. A window shade support, comprising a pair of brackets of angle iron and each having 30 its ends set off and secured to the sides of the window casing, hangers mounted to slide on the brackets and having bearings for the shade roller, each hanger having an L-shaped plate fitting against the back and

angular side of the corresponding bracket, 35 the plate being provided with bent over flanges fitting the side edges of the brackets, cords secured to the said brackets, a pulley on the upper end of each of the brackets and over which passes the adjacent cord, 40 one of said cords extending across the top of the window casing and over the other pulley, housings for the said pulleys, and fastening means for securing the ends of the brackets to the window casing, the fastening means on the upper ends of the brackets also fastening the pulley housing in place and forming the axles for the pulleys to turn on.

3. A window shade support, comprising a 50 pair of brackets of angle iron each having its ends set off and secured to the sides of the window casing, hangers mounted to slide on the brackets and having bearings for the shade roller, each hanger consisting of an L-shaped plate fitting adjacent to the back and angular side of the corresponding bracket, the plate being provided with bent over flanges fitting the side edges of the brackets, and means for simultaneously 55 raising and lowering the said hangers.

In testimony whereof I have signed my name to this specification in the presence of two subscribing witnesses.

CHARLES CORRIE BROWN.
